PORTABLE BUILDING STRUCTURE

Ward Clinton Smith, Detroit, Mich., assignor to
Stout Houses, Incorporated, Detroit, Mich., a
corporation of Michigan

Application January 31, 1944, Serial No. 520,491,
which is a division of application Serial No.
483,636, April 19, 1943. Divided and this ap-
plication October 30, 1944, Serial No. 560,967

6 Claims. (Cl. 108—12)

1

This invention relates generally to portable building structures of the type that may be transported or shipped by the manufacturer in unassembled or knockdown condition and may be readily and quickly assembled by unskilled labor wherever they are to be erected or used, and constitutes a division of my application filed January 31, 1944, bearing Serial No. 520,491, which is a division of my application filed April 19, 1943, bearing Serial No. 483,636.

One of the essential objects of the invention is to provide a sectional roof structure wherein an improved joint between the roof sections enables narrower roof sections to be employed than heretofore.

Another object is to provide a roof structure wherein the joint between the roof sections includes means for urging the roof sections into proper assembled relation with an intermediate common support therefor.

Another object is to provide a roof structure wherein the joint between the roof sections includes means for carrying to the outer side of a supporting wall for said sections any moisture seeping down the joints between said roof sections.

Another object is to provide a roof structure that is simple in construction, economical to manufacture, easy to erect, and efficient in use.

Other objects, advantages and novel details of construction of this invention will be made more apparent as this description proceeds, especially when considered in connection with the accompanying drawing, wherein:

Fig. 1 is a fragmentary perspective view of a building structure embodying my invention;

Fig. 2 is a cross sectional view through the structure.

Referring now to the drawing, A is an upright wall, B and C respectively are adjacent roof sections extending over said wall, D is a rafter on said wall and serving as a common support for said roof sections, E and F respectively are filler strips on top of said rafter between the roof sections, and H is a batten or cover strip for the joint between the roof sections.

As shown, the upright wall A has adjacent sections 10 and 11 respectively and a cover strip 12 concealing the joint between said sections, however such wall may be any suitable construction, as desired.

The room sections B and C have roof panels 13 and 14 respectively provided at their adjacent edges with longitudinally extending frame members 15 and 16 respectively having tongues 15'

and 16' that overhang and have tongue and groove connections with the underlying laterally projecting edge portions 17 and 18 respectively of the rafter D. Preferably the rafter D is supported upon and inclines upwardly and rearwardly from the upright wall A. The laterally projecting edge portions 17 and 18 respectively of the rafter are provided substantially in vertical alignment with the inner edges of the roof sections with longitudinally extending grooves 19 and 20 respectively that catch and carry to the outside of the upright wall A any moisture draining down from the adjacent edges of said roof sections. Preferably the outer side walls 21 and 22 respectively of the grooves 19 and 20 are inclined and serve as cams for the tongues 15' and 16' to urge the frame members 15 and 16 respectively of the roof sections into proper assembled relation against the rafter D.

20 The filler strips E and F are in edge to edge relation on top of the rafter D between and in edge to edge relation with the panels 13 and 14 respectively of the roof sections, while the cover strip H is on top of the filler strips E and F and overlaps the panels 13 and 14 of the roof sections. Any suitable means such as the headed elements 23 may be employed to secure the cover strip H to the roof sections.

Thus, from the foregoing, it will be apparent that the tongues 15' and 16' of the roof sections will be in separate grooves or channels 19 and 20 respectively at opposite side edges of the intermediate rafter D, instead of meeting or abutting in a single channel or groove at the center of the rafter. Hence, the connections between the roof sections B and C and intermediate rafter D permit narrower roof sections to be used than heretofore. As a result, a substantial saving in the cost of roof panels, such as 13 and 14 respectively is obtained. Moreover, the tongue and groove connections between the roof sections and the rafter are such that the grooves 19 and 20 not only receive and hold the tongues 15' and 16', but also serve as drainage channels for moisture seeping down from adjacent edges of the roof sections. In addition, the outer walls 21 and 22 respectively of the grooves serve as cams for the tongues 15' and 16' to urge the roof sections into a proper assembled relation with the intermediate rafter D. The cover strip H conceals the connections between the roof sections and rafter to provide a neat appearance, and the securing elements 23 for such cover strip cooperate therewith and with the panel sections

13 and 14 to maintain the parts in assembled relation.

What I claim as my invention is:

1. A roof structure comprising a solid rafter of substantially rectangular cross section provided throughout its length at opposite side edges thereof with longitudinally extending lateral projections, the upper faces of said projections being provided throughout their length beside the adjacent side edges of the rafter with upwardly opening longitudinally extending drainage grooves and provided along the outer sides of and substantially parallel to said grooves with longitudinally extending upstanding tongues, the outer side walls of said grooves being inclined upwardly and outwardly, roof panels overlying and projecting laterally outward from said lateral projections, said roof panels being spaced laterally apart and provided at their adjacent edges with elongated frame members of inverted substantially L cross section, the bases of said inverted L-shaped members being provided throughout their length at their outer edges with depending longitudinally extending tongues and provided along the inner sides of and substantially parallel to said depending tongues with longitudinally extending downwardly opening grooves, said depending tongues engaging the upwardly opening grooves aforesaid and forced by the inclined outer side walls thereof against opposite side edges of said rafter, the depth of said depending tongues being less than the depth of said drainage grooves whereby a drainage space is provided between said depending tongues and the bottom of said grooves for water from the roof panels, said downwardly opening grooves receiving the upstanding tongues aforesaid and cooperating with the tongue and groove connection previously mentioned to provide dual interlocks between the roof panels and said rafter at opposite side edges of the latter, means on the rafter filling the space between the roof panels, and a batten strip overlapping said filling means and roof panels and secured to the latter.

2. A roof structure comprising a rafter provided throughout its length at opposite side edges thereof with longitudinally extending lateral projections, the upper faces of said projections being provided throughout their length beside the adjacent side edges of the rafter with upwardly opening longitudinally extending drainage grooves and provided along the outer sides of and substantially parallel to said grooves with longitudinally extending upstanding tongues, the outer side walls of said grooves being inclined upwardly and outwardly, roof panels overlying and projecting laterally outward from said lateral projections, said roof panels being provided at their adjacent edges with elongated frame members of inverted substantially L cross section, the bases of said inverted L-shaped members being provided throughout their length at their outer edges with depending longitudinally extending tongues and provided along the inner sides of and substantially parallel to said depending tongues with longitudinally extending downwardly opening grooves, said depending tongues engaging the upwardly opening grooves aforesaid and forced by the inclined outer side walls thereof against opposite side edges of said rafter, the depth of said depending tongues being less than the depth of said drainage grooves whereby a drainage space is provided between said depending tongues and the bottoms of said grooves for water from the roof panels, said downwardly

opening grooves receiving the upstanding tongues aforesaid and cooperating with the tongue and groove connection previously mentioned to provide dual interlocks between the roof panels and said rafter at opposite side edges of the latter, and a batten strip overlapping adjacent edges of said roof panels and secured to the latter.

3. A roof structure comprising a rafter provided at opposite side edges thereof with longitudinally extending lateral projections, the upper faces of said projections being provided beside the adjacent side edges of the rafter with upwardly opening longitudinally extending drainage grooves and provided along the outer sides of said grooves with longitudinally extending upstanding tongues, the outer side walls of said grooves being inclined upwardly and outwardly, roof panels overlying and projecting laterally outward from said lateral projections, said roof panels being provided at their adjacent edges with elongated frame members of inverted substantially L cross section, the bases of said inverted L-shaped members being provided at their outer edges with depending longitudinally extending tongues and provided along the inner sides of said depending tongues with longitudinally extending downwardly opening grooves, said depending tongues engaging the upwardly opening grooves aforesaid and forced by the inclined outer side walls thereof against opposite side edges of said rafter, said downwardly opening grooves receiving the upstanding tongues aforesaid and cooperating with the tongue and groove connection previously mentioned to provide dual interlocks between the roof panels and said rafter at opposite side edges of the latter, and a batten strip overlapping adjacent edges of said roof panels and secured to the latter.

4. A roof structure comprising a rafter provided at opposite side edges thereof with longitudinally extending lateral projections, the upper faces of said projections being provided beside the adjacent side edges of the rafter with upwardly opening longitudinally extending drainage grooves and provided at the outer sides of said grooves with longitudinally extending upstanding tongues, the outer side walls of said grooves being inclined upwardly and outwardly, roof panels overlying and projecting laterally outward from said lateral projections, said roof panels being provided at their adjacent edges with depending longitudinally extending tongues and provided along the inner sides of said depending tongues with longitudinally extending downwardly opening grooves, said depending tongues engaging the upwardly opening grooves aforesaid and forced by the inclined outer side walls thereof against opposite side edges of said rafter, said downwardly opening grooves receiving the upstanding tongues aforesaid and cooperating with the tongue and groove connection previously mentioned to provide dual interlocks between the roof panels and said rafter at opposite side edges of the latter, and a batten strip overlapping adjacent edges of said roof panels and secured to the latter.

5. A roof structure comprising a rafter provided at opposite side edges thereof with longitudinally extending lateral projections, the upper faces of said projections being provided beside the adjacent side edges of the rafter with upwardly opening longitudinally extending drainage grooves and provided at the outer sides of said grooves with longitudinally extending upstanding tongues, roof panels overlying and pro-

jecting laterally outward from said lateral projections, said roof panels being provided at their adjacent edges with depending longitudinally extending tongues and provided along the inner sides of said depending tongues with longitudinally extending downwardly opening grooves, said depending tongues engaging the upwardly opening grooves aforesaid, said downwardly opening grooves receiving the upstanding tongues aforesaid and cooperating with the tongue and groove connection previously mentioned to provide dual interlocks between the roof panels and said rafter at opposite side edges of the latter, and a batten strip overlapping adjacent edges of said roof panels and secured to the latter.

6. A roof structure comprising a rafter provided at opposite side edges thereof with longitudinally extending lateral projections, the upper faces of said projections being provided beside the adjacent side edges of the rafter with upwardly opening longitudinally extending drainage

grooves and provided at the outer sides of said grooves with longitudinally extending upstanding tongues, roof panels overlying and projecting laterally outward from said lateral projections, said roof panels being provided at their adjacent edges with elongated frame members having depending longitudinally extending tongues and provided along the inner sides of said depending tongues with longitudinally extending downwardly opening grooves, said depending tongues engaging the upwardly opening grooves aforesaid, said downwardly opening grooves receiving the upstanding tongues aforesaid and cooperating with the tongue and groove connection previously mentioned to provide dual interlocks between the roof panels and said rafter at opposite side edges of the latter, and a batten strip overlapping adjacent edges of said roof panels and secured to the latter.

WARD CLINTON SMITH.
